DESIGN FOR A GOBLET OR SIMILAR ARTICLE

Rowena Reed Kostellow, Pittsburgh, Pa., assignor to United States Glass Co., Pittsburgh, Pa., a corporation of Pennsylvania

Application February 16, 1938, Serial No. 75,183

Term of patent 3½ years

To all whom it may concern:

Be it known that I, Rowena Reed Kostellow, a citizen of the United States, residing at Pittsburgh, Allegheny County, State of Pennsylvania, have invented a new, original, and ornamental Design for a Goblet or Similar Article, of which the following is a specification, reference being had to the accompanying drawing, forming a part thereof, in which:

Fig. 1 is a side elevation of a goblet embodying my new design;

Fig. 2 is a fragmentary side elevation of the goblet shown in Fig. 1 turned through 90°; and

Fig. 3 is a section on the line 3—3 of Fig. 1 looking in the direction of the arrows.

The characteristic feature of my new design resides in the pattern shown in full lines on the drawing.

What I claim is:

The ornamental design for a goblet or similar article, substantially as shown and described.

ROWENA REED KOSTELLOW.
